DESIGN FOR A SOAP CAKE HOLDER

Harry H. Gray, Kansas City, Mo.

Application November 15, 1945, Serial No. 123,797

Term of patent 7 years

(Cl. D4—3)

To all whom it may concern:

Be it known that I, Harry H. Gray, a citizen of the United States and a resident of Kansas City, Jackson County, Missouri, have invented a new, original, and ornamental Design for a Soap Cake Holder, of which the following is a specification, reference being had to the accompanying drawing, forming a part thereof.

In the said drawing—

Figure 1 is a side elevation of the soap cake holder showing my new design.

Figure 2 is a front view of the soap cake holder.

Figure 3 is a top plan view of the soap cake holder.

Figure 4 is a rear elevation of the soap cake holder.

I claim:

The ornamental design for a soap cake holder, substantially as shown.

HARRY H. GRAY.
